Léon Gosselin
ATTORNEY

UNITED STATES PATENT OFFICE

ANDRÉ LENIEF, OF PARIS, FRANCE

SECURING DEVICE FOR SUSPENDERS

Application filed January 4, 1930, Serial No. 418,584, and in France January 8, 1928.

This invention relates to a securing device for suspenders and the like, and its object is to provide a securing device more especially adapted to be used for suspenders but which can be used as a fastening for belts, straps, bag mountings, etc.

Said device is essentially characterized by the feature that it comprises a mounting provided with a movable part adapted, on being rotated, to cause the bringing together of two or more swinging jaws that grip the neck of a stud and hold the fabric of the article to be secured in a housing provided for the purpose and which may or may not cover the stud, or to cause the said jaws to be forced apart when release of the stud and removal of the fabric are desired.

In order to make my invention more clearly understood I have illustrated, as an example, an embodiment thereof in and by drawings appended hereto and wherein:

Figure 1 is a horizontal section on line A—B of Figure 2, with the stud 6 gripped between the jaws;

Figure 2 is a vertical section on line C—D of Figure 1, the movable part 10 being shown in closed position;

Figure 3 is a view similar to Figure 1, but with the jaws drawn apart and the stud released.

My device comprises a substantially flat front plate 1 which, at its forward portion 2, is provided with a hole 5. A stud 6 is adapted to extend through the hole 5 and to be latched by two jaws or latching members 4 which are pivoted on pivots 3. The stud 6 is attached to a stud supporting member 7 which is pivoted or otherwise detachably secured to the front plate 1. Thus, the front plate 1 and the stud supporting member 7 may be attached, respectively, to the opposite sides of a hand-bag to form a closure therefor. When the invention is applied to a garter or suspender, the front plate 1 and the stud supporting member 7 are hingedly secured to the suspender or garter 8. A rotatable cover is attached to the front plate 1. The cover 10 is apertured, as shown in Fig. 2, to receive the head of the stud 6. The underside of the rotatable cover 10 is fitted with

two small spindles 11 which carry rollers 12 which are adapted to ride on the cam-shaped edges 13 of the latching members or jaws 4. The cover 10 is attached to the front member 1 by two small lugs 14 screwed into or otherwise fixed on the cover 10 and engaging in a circular groove 15 in the front member 1. As shown in the figures, particularly Fig. 2, the jaws or latching members 4 can swing about their pivots 3, which are fixed in the forward portion 2 of the base member 1 so as to grip or release the neck of the stud 6.

The operation of the above described device is as follows:

Supposing it to be in the position illustrated by Figure 3, then, in the case of a suspender, I pass the edge of the stocking or of the sock over the head of the stud 6 which I next introduce, so furnished, into the hole 5 of base member 1, whereupon I rotate cover 10 the required distance in the direction indicated by the arrow f; the rollers 12 ride on the side edges 13 of the jaws 4 and cause the latter to swing round their pivots 3; as cover 10 is rotated, the jaws come together and grip the neck of stud 6. The device is then in the position shown by Figure 1.

In order to release stud 6 I proceed inversely, the jaws 4 being swung back by the action exerted by the rollers when the cover 10 is turned in the direction opposite to the closing motion.

It should be noted that, in the position illustrated by Figure 1, the rollers 12 are resting on flat edge portions 12' provided adjacent the ends of jaws 4. Owing to this arrangement it will be realized that said rollers can only roll back to part the jaws and thereby release the stud 6 under the aforesaid action exerted on the rollers when cover 10 is turned in the direction opposite the closing motion and to an extent sufficient to force the rollers past the flat edge portions 12'.

It should be noted, furthermore, that the jaws 4 are each provided with a notch 4'. These notches are so arranged that when the rollers 12 are rolled back for opening the jaws, they come to bear on the curved part of the said notches, thereby compelling the jaws to open completely (Figure 3).

Obviously the above disclosed device may be used as a clasp for handbags and other like purposes, the stud and the female part (i. e., the jaws) intended to receive and to lock it being respectively secured to the two parts of the bag to be fastened.

Having now particularly ascertained and described the nature of my said invention as well as the manner in which the same is to be performed, I declare that what I claim is:

1. A separable fastener, comprising a stud supporting member; a headed stud carried thereby; a front plate member provided with a forward portion having a central opening through which the stud projects; a pair of reversely-arranged latching members pivotally mounted at one of their ends on the plate member on opposite sides of the stud, each latching member having a cam-shaped edge portion; a cover rotatably connected with the front plate; and a pair of oppositely-located depending rollers carried within the cover for coaction with the cam-shaped edges of the latching members to move said latching members toward or from each other according to the direction of rotation of said cover and thereby grip or release the stud.

2. A separable fastener, according to claim 1, in which each latching member is provided adjacent its pivoted end with a curved notch to coact with the respective roller in completely opening the corresponding latching member.

3. A separable fastener, comprising a stud supporting member, a headed stud carried thereby; a front plate member provided with a forward portion having a central opening through which the stud projects; a pair of reversely-arranged latching members pivotally mounted at one of their ends on the front plate on opposite sides of said stud, each latching member having a flat-edged portion and a cam-shaped edge portion terminating at the flat edge portion; a cover rotatably connected with the front plate member; and a pair of oppositely-located depending rollers carried by the cover for coaction with the flat edge portions and cam-shaped edge portions of the latching members to move said latching members toward or from each other according to the direction of rotation of said cover and thereby grip or release the stud.

In testimony whereof, I affix my signature.

ANDRÉ LENIEF.
